STOP MOTION

William A. Zieve, North Bergen, N. J.

Application June 12, 1935, Serial No. 26,195

10 Claims. (Cl. 66—163)

This invention relates to stop-motions, and is adapted generally for use in connection with machines of the type which depend for their proper operation on the presence and normal behavior of a traveling flexible element in connection with which the machine is adapted to cooperate.

Although the invention is fundamentally such that it may be adapted for various uses, it is herein illustrated as embodied in a stop-motion for knitting machines.

Generally stated, an important object of the invention is to provide a stop-motion which is simple in construction, reliable in operation and sensitive to abnormal conditions that may arise in connection with the traveling flexible element upon the presence and normal behavior of which the machine depends for its proper operation.

Further and more particularly stated, an important object of the invention is to provide a stop-motion for use with knitting machines which is not only simple in construction, reliable in operation and sensitive to abnormal conditions that may arise in connection with the traveling flexible element, namely, the knitting thread, but which is also such as to allow the knitting requirements of the machine to be met when operating under its own momentum pursuant to any throw-out operation that may be effected incident, for example, to a running out or breaking of the knitting thread or to the setting up of an undue impedance to its travel such as may be occasioned by the existence of a knotted or entangled thread at the bobbin or other source of thread supply.

Other objects and advantages of the invention will become apparent from the following description when taken in connection with the accompanying drawing, in which—

Fig. 1 is a side elevation of a stop-motion embodying the present invention and particularly adapted for use in connection with a knitting machine; Fig. 2 is an elevation of the device of Fig. 1 as viewed from the left therein; Fig. 3 is a fragmental view showing in elevation the rear of the upper end of the device, particular reference being had to Fig. 1; Fig. 4 is a sectional view taken on line 4—4 of Fig. 3, and Fig. 5 is a perspective view of a carriage unit and its associated thread guides.

Although as many of the devices embodying the present invention may be associated with a given machine as are necessary to fully equip that machine, only one such device is herein

illustrated, it being designed especially for a knitting machine, not shown, with which there may be associated one device for each knitting thread or "end" employed.

Referring to the drawings, the numeral 5 indicates a bracket, including a guide rail 6 terminating at its upper and lower ends in the arms 7 and 8, respectively, by which the device may be attached to a suitable part of a knitting machine. Secured to the upper arm 7 is a sheave 10 support or bracket 10, having a spindle 11 on which is carried a sheave 12, of suitable material which is relatively light in weight. In line with the sheave 12 is a similar sheave 14, mounted on a spindle 15, secured to the lower end of a tensioning arm 16, pivotally connected, as at 17, to the arm 8, the upper end of the arm 16 being provided with an adjustable stop 18, in the form of a set screw, which carries a lock nut 20 and the lower end of which is adapted to engage 20 the arm 8, as and for the purpose hereinafter more particularly described.

Carried on the guide rail 6, is a slidable carriage 21 which includes a slide 22, the longitudinal margins of which are bent up so as to provide reinforcing ribs 24 extending substantially throughout the extent of the carriage. The slide 22 is provided at its upper and lower ends with wings 25, which are bent rearwardly and inwardly, as viewed in Fig. 5, so as to form a pair 30 of guide sleeves 26, which are adapted to embrace the guide rail 6 and retain the carriage thereon for vertical movement.

Associated with the carriage 21, is a pair of porcelain thread guides 27 and 28, through which a knitting thread 30 is adapted to travel from its source, such as a bobbin 31, into the knitting machine to be there acted on in the carrying out of the ordinary knitting operation. The thread guides 27 and 28 are held in alignment with each other and in association with the carriage 21 by a pair of U-shaped cradles 32 and 34, which are open at their upper ends so as to permit the guides to be easily placed in or removed from their functioning positions as occasion may require. The cradles 32 and 34 constitute parts of a thread-guide support 35, which is constructed of suitable material, such as wire, and includes a connector element 36, terminating at its lower and upper ends in horizontally disposed arms 37 and 38, the former of which is formed integral with a vertical leg 40, with the upper end of which the cradle 32 is integrally formed, and the latter of which is integral with the cradle 34. The connector element 36 is accommodated intermediate the re-

inforcing ribs 24 and the thread-guide support in its entirety is held in a permanently fixed relation on the carriage 21 by a pair of wings 41 and 42 which are formed integral with the slide 22 and are 5 looped about the horizontally disposed arms 37 and 38 respectively.

In order that the carriage 21 may be normally held in its position shown in Fig. 1, it is connected in one reach of a cable-like element 43, in the 10 form of a light but relatively strong cord which is carried by the sheaves 12 and 14, the other reach of the cable-like element being accommodated by openings 47-44, in the upper and lower arms 7 and 8, and carrying an actuating 15 weight 45. The actuating weight 45 is sufficiently heavy to normally maintain the carriage 21 in its position shown in Figs. 1 to 3 and yet sufficiently light to permit the carriage to move downwardly under the influence of any undue tension that 20 may be set up in the knitting thread 30, as when a knotted or entangled thread condition is encountered at the bobbin 31.

The actuating weight 45 is herein shown as including a link 46, the lower or eyelet-end of which 25 is connected to the cable-like element 43 and the upper or hook-like end of which is detachably connected to the adjacent end of the cable-like element through the medium of a connector link 47. On the shank or stem portion of the link 46, are a 30 plurality of disc-like weight elements in the form of ordinary washers 48, the number of which may be varied in order to establish the overbalanced relation, in favor of the actuating weight 45 as against the carriage 21, which is best suited 35 to actual operating conditions. In this connection, it is to be noted that when a change over from a relatively heavy knitting thread to a relatively light knitting thread is made, it may be desirable to remove certain of the washers 48 so that the carriage 21 will move downwardly more 40 readily under the influence of undue tension in the knitting thread; whereas if a change over from a relatively light thread to a relatively heavy thread is made, it may be desirable to supply additional washers 48 so as to render the 45 carriage responsive to a predetermined tension of greater magnitude. By unhooking the upper or hook-like end of the link 46 from the connector link 47, certain of the washers 48 may be removed or other washers may be added as occasions may 50 require, the number of washers and therefore the effectiveness of the weight 45 being governed or determined, at least in part, by the tensile strength of the knitting thread employed so as to insure 55 downward movement of the carriage 21 under the action of thread-tension of a predetermined and somewhat less value than that which corresponds to the minimum tensile strength of the particular thread employed.

From the foregoing, it will be understood that 60 the point, considered in terms of tensile strength of the knitting thread at which the carriage 21 will respond to undue tension set up in the knitting thread may be conveniently predetermined, thus rendering the device capable of universal use, in 65 so far as the range in size or tensile strength of the knitting threads is concerned.

In order that operation of the carriage 21, or 70 downward movement thereof under the influence of undue thread tension, or a break in the knitting thread or a run-out of such thread, may exercise a control-function in stopping the operation of the knitting machine, there is provided control means which may include a normally open switch S, housed within a switch box 50, supported as by a 75 bracket 51, connected to the arm 7, the switch

box being conveniently located and having a door-like closure 52 which may be opened in order to permit inspection of the switch, if and when desired. The switch S includes a terminal 54, secured to and insulated from the rear wall of the 5 switch box, and connected to one end of a yieldable contact 55, in the form of a coil spring which is located within the switch box and is there adapted to be engaged by the upper horizontally disposed end 56 of a movable contact or switch arm 57. 10 The switch arm 57 is connected to a horizontally disposed shaft-like element 58, journaled in a bearing sleeve 60, carried by the rear wall of the switch box, the shaft-like element 58 being connected at a point outside of the switch box to a 15 thread-engaging arm 61, normally disposed intermediate the thread guides 27 and 28 and there supported by that portion of the knitting thread 30 which bridges the space or gap intermediate such guides, whereby the switch arm 57 is held in 20 open-circuit position as shown in Fig. 1. Inasmuch as the switch S may be employed in association with various types of throw-out mechanisms, among which may be mentioned magnetic clutches, it is deemed unnecessary to indicate 25 herein more than the actuating lever 62 of such a clutch, which, as will be observed from Fig. 1, is shown in association with a control circuit, including a magnet 64 which may be grounded to the frame work of the knitting machine, as shown 30 at G, and connected through a source of electrical energy B by conductors 65 and 66 to the terminal 54 of the switch box 50, which in turn is grounded through the knitting machine when the device embodying the present invention is installed 35 thereon.

From the foregoing, it will be understood that the device when conditioned for use, as shown in Figs. 1 and 2, is adapted to exercise a positive control over the knitting machine to stop the 40 same under abnormal operating conditions, as when the knitting thread runs out or is broken or is subjected to undue tension. In the event the thread runs out, or is broken, the thread-engaging arm 61, which is normally supported by 45 such thread at a point intermediate the thread guides 27 and 28, is permitted to drop under its own weight, thereby moving the contact arm 57 into engagement with the contact 55 and thus closing the circuit through the magnet 64 to 50 effect the stopping operation of the throw-out mechanism, not shown, through the instrumentality of its actuating lever 62 which is moved as an armature under the action of the magnet 64. Should the thread become subjected to 55 undue tension resulting, for example, from a knotted or entangled thread condition at the source of supply, the carriage 21 will move downwardly, as the tensioned thread is supplied to or consumed by the knitting machine in the knitting 60 operation, thus allowing the thread-engaging arm 61 to so move under the action of gravity as to effect engagement of the contact arm 57 with the contact 55 incident to which the throw-out mechanism, not shown, is actuated incident to 65 energization of the magnet 64, as previously described.

Although the operation of the device is described with respect to only a single unit, it will be understood that operation of the throw-out 70 mechanism, of which the actuating lever 62 constitutes a part, may be effected in response to the operation of any one of a battery of the present devices, as will be readily understood when it is taken into account that all of the switch box 75

terminals 54 may be connected to the conductor 66, so that the closing of any switch S will result in energization of the magnet 64 and simultaneous operation of the throw-out mechanism 5 of which the actuating lever 62 forms a part.

Although only one form of the invention is herein shown and described, it will be understood that various changes may be made without departing from the spirit of the invention or the 10 scope of the following claims.

What is claimed is:

1. In a stop-motion under the control of a traveling flexible element, a flexible-element retaining unit mounted for translatory movement 15 under the influence of abnormal tension conditions in said flexible element and with relation to which said flexible element is adapted to travel and by which such element is normally held in a definite path of movement, constant-force-exercising means tending to maintain said unit in a position corresponding to said definite path of movement and adapted to offer uniform resistance to translatory movement of said unit throughout its extent of travel as effected in 20 response to abnormal tension-conditions in said flexible element, and throw-out-actuating-mechanism-control-means adapted to cooperate with and to be normally maintained in an ineffective position by said flexible element while that element is held in said definite path of movement and adapted to move to an effective position incident to translatory movement of said unit in response to abnormal tension-conditions in said flexible element.

2. In a stop-motion under the control of a traveling flexible element, a guide, a flexible-element retaining unit slidably mounted on said guide for translatory movement under the influence of abnormal tension conditions in said flexible element and with relation to which said flexible element is adapted to travel and by which such element is normally held in a definite path of movement, constant-force-exercising means tending to maintain said unit in a position corresponding to said definite path of movement and adapted to offer uniform resistance to translatory movement of said unit throughout its extent of travel as effected in response to abnormal tension-conditions in said flexible element, and throw-out-actuating-mechanism-control-means adapted to cooperate with and to be normally maintained in an ineffective position by said flexible element while that element is held in said definite path of movement and adapted to move to an effective position incident to translatory movement of said unit in response to abnormal tension-conditions in said flexible element.

3. In a stop-motion under the control of a traveling flexible element, a guide, a flexible-element retaining unit slidably mounted on said guide for translatory movement under the influence of abnormal tension conditions in said flexible element and by which such element is normally held in a supported position, constant-force-exercising means tending to maintain said unit together with said supported element in an elevated position on said guide and adapted to offer uniform resistance to such downward movement of said unit together with said supported element as is effected in response to abnormal tension-conditions in said flexible element, and throw-out-actuating-mechanism-control-means adapted to cooperate with and to be normally maintained in an ineffective position by said 75 supported element prior to downward movement

of said unit in response to abnormal tension-conditions in said flexible element and adapted to move to an effective position incident to such downward movement of said unit.

4. In a stop-motion under the control of a traveling flexible element, a flexible-element retaining unit mounted for translatory movement under the influence of abnormal tension conditions in said flexible element and with relation to which said flexible element is adapted to travel and by which such element is normally held in a definite path of movement, constant-force-exercising means tending to maintain said unit in a position corresponding to said definite path of movement and adapted to offer uniform resistance to translatory movement of said unit throughout its extent of travel as effected in response to abnormal tension-conditions in said flexible element, and throw-out-actuating-mechanism-control-means adapted to cooperate with and to be normally maintained in an ineffective position by said flexible element while that element is held in said definite path of movement and adapted to move to an effective position incident to translatory movement of said unit in response to abnormal tension-conditions in said flexible element as well as incident to the release of normal tension in said flexible element.

5. In a stop-motion under the control of a traveling flexible element, a guide, a flexible-element retaining unit slidably mounted on said guide for translatory movement under the influence of abnormal tension conditions in said flexible element and with relation to which said flexible element is adapted to travel and by which such element is normally held in a definite path of movement, constant-force-exercising means tending to maintain said unit in a position corresponding to said definite path of movement and adapted to offer uniform resistance to translatory movement of said unit throughout its extent of travel as effected in response to abnormal tension-conditions in said flexible element, and throw-out-actuating-mechanism-control-means adapted to cooperate with and to be normally maintained in an ineffective position by said flexible element while that element is held in said definite path of movement and adapted to move to an effective position incident to translatory movement of said unit in response to abnormal tension-conditions in said flexible element as well as incident to the release of normal tension in said flexible element.

6. In a stop-motion under the control of a traveling flexible element, a guide, a flexible-element retaining unit slidably mounted on said guide for translatory movement under the influence of abnormal tension conditions in said flexible element and by which such element is normally held in a supported position, constant-force-exercising means tending to maintain said unit together with said supported element in an elevated position on said guide and adapted to offer uniform resistance to such downward movement of said unit together with said supported element as is effected in response to abnormal tension-conditions in said flexible element, and throw-out-actuating-mechanism-control-means adapted to cooperate with and to be normally maintained in an ineffective position by said supported element prior to downward movement of said unit in response to abnormal tension-conditions in said flexible element and adapted to move to an effective position incident to such downward movement of said unit as well as in-

cident to the release of normal tension in said flexible element.

7. In a stop-motion under the control of a traveling flexible element, a vertically disposed 5 guide, a flexible-element retaining unit slidably mounted on said guide for translatory movement under the influence of abnormal tension conditions in said flexible element and by which such element is normally held in a supported position, 10 said unit including a pair of guide elements spaced from each other and through which said flexible element is adapted to travel, constant-force-exercising means tending to maintain said unit together with said supported element in an 15 elevated position on said guide and adapted to offer uniform resistance to such downward movement of said unit together with said supported element as is effected in response to abnormal tension-conditions in said flexible element, 20 and throw-out-actuating-mechanism-control-means including a switch unit comprising a switch-actuating arm normally supported and maintained in open-circuit position by that portion of said flexible element bridging the space 25 intermediate said guide elements and adapted to move to closed-circuit position incident to downward movement of said unit in response to abnormal tension-conditions in said flexible element.
- 30 8. In a stop-motion under the control of a traveling flexible element, a vertically disposed 30 guide, a flexible-element retaining unit slidably mounted on said guide for translatory movement under the influence of abnormal tension conditions 35 in said flexible element and by which such element is normally held in a supported position, said unit including a pair of guide elements spaced from each other and through which said flexible element is adapted to travel, constant- 40 force-exercising means tending to maintain said unit together with said supported element in an elevated position on said guide and adapted to offer uniform resistance to such downward movement of said unit together with said supported 45 element as is effected in response to abnormal tension-conditions in said flexible element, and throw-out-actuating-mechanism-control-means including a switch unit comprising a switch-actuating arm normally supported and maintained 50 in open-circuit position by that portion of said flexible element bridging the space intermediate said guide elements and adapted to move to closed-circuit position incident to downward movement of said unit in response to abnormal 55 tension-conditions in said flexible element as well as incident to the release of normal tension in said flexible element.
9. In a stop-motion under the control of a traveling flexible element, a vertically disposed 60 guide, a flexible-element retaining unit slidably

mounted on said guide and by which such element is normally held in a supported position, said unit including a pair of guide elements spaced from each other and through which said flexible element is adapted to travel, a pair of 5 sheaves one of which is supported at the upper end of said guide and the other of which is supported at the lower end thereof, a cable-like element carried by said sheaves and in one reach of which said unit is connected, an actuating 10 weight connected in the other reach of said cable-like element and tending to maintain said unit together with said supported element in an elevated position on said guide and adapted to move incident to downward movement of said 15 unit together with said supported element in response to abnormal tension-conditions in said flexible element, and throw-out-actuating-mechanism-control-means including a switch unit comprising a switch-actuating arm normally 20 supported and maintained in open-circuit position by that portion of said flexible element bridging the space intermediate said guide elements and adapted to move to closed-circuit position incident to downward movement of said unit in response to abnormal tension-conditions in said flexible element.

10. In a stop-motion under the control of a traveling flexible element, a vertically disposed 30 guide, a flexible-element retaining unit slidably mounted on said guide and by which such element is normally held in a supported position, said unit including a pair of guide elements spaced from each other and through which said flexible element is adapted to travel, a pair of 35 sheaves one of which is supported at the upper end of said guide and the other of which is supported at the lower end thereof, a cable-like element carried by said sheaves and in one reach of which said unit is connected, an actuating weight 40 connected in the other reach of said cable-like element and tending to maintain said unit together with said supported element in an elevated position on said guide and adapted to move incident to downward movement of said unit together with said supported element in response to abnormal tension-conditions in said flexible element, and throw-out-actuating-mechanism-control-means including a switch unit comprising a switch-actuating arm normally supported and 45 maintained in open-circuit position by that portion of said flexible element bridging the space intermediate said guide elements and adapted to move to closed-circuit position incident to downward movement of said unit in response to abnormal tension-conditions in said flexible element as well as incident to the release of normal 50 tension in said flexible element.
